JOHN H. BLEDSOE AND MARTIN HAUSER, OF KANSAS CITY, MISSOURI.

AIR-TRAP.

1,364,690.

Specification of Letters Patent.

Patented Jan. 4, 1921.

Application filed March 26, 1917. Serial No. 157,381.

To all whom it may concern:

Be it known that we, JOHN H. BLEDSOE and MARTIN HAUSER, citizens of the United States, residing at Kansas City, in the county of Jackson and State of Missouri, have invented certain new and useful Improvements in Air-Traps; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to steam heating systems and more particularly to what may be termed a one pipe automatic vacuum system, the principal object of the invention being to provide means whereby steam or vapor may be circulated quickly through a pipe and radiator system at any pressure or vacuum as the weather may require and by which all or any fractional part of a radiator in the system may be heated.

In accomplishing this object, we have provided improved detail of structure, the preferred forms of which are illustrated in the accompanying drawings, wherein—

30 Figure I is a perspective, diagrammatic view of a heating system embodying the present invention.

Fig. II is an elevation of the system control parts, showing their connection with each other and with the boiler, the parts being shown in partial section for better illustration.

Fig. III is a detail perspective view of the separator float and its mounting.

40 Referring more in detail to the drawings—
1 designates a boiler of any approved type for steam heating purposes, 2 a steam supply main leading from the boiler and having risers 3 connected therewith, which lead to 45 and have top and bottom connections respectively through valves 4 and 5 with radiators 6.

The valve 4 through which steam from the boiler is admitted to the radiator, may be 50 of any general type.

The receiver separator 27, wherein the water of condensation and air discharged from the radiator is received, comprises a cylindrical body having an opening 28 adjacent the top for receiving the pipe 26 and a base opening 29 for receiving a pipe 30,

whereby the water is delivered back to the boiler, the pipe 30 being provided with a check valve 30' whereby the flow of water therethrough is normally prevented.

60 Threaded into an opening 31 at the top of the receiver, is a collar 32, whereby the valve proper is supported and having at its lower end a valve seat 33 which opens into a socket 34 into which a vent 35 is threaded, whereby 65 air may be delivered from the receiver; the said vent pipe leading to a thermostatic check valve 36 that is operable under influence of steam to close the vent pipe and prevent the escape of steam from the receiver 70 and heating system, although the vent pipe is normally retained open in order to permit the escape of air from the receiver and heating system.

75 Suspended from the collar 32 is a cage 38, comprising wires having their upper ends secured to the collar and their lower ends crossed to form a support, and slidably within the cage is a float 39, comprising a cylindrical, metal body, having a frusto-conical 80 upper end 40, adapted for seating in the valve seat 33 of the collar 32, and having a similar lower end 41 adapted for supporting engagement with the bottom of the cage; the points of contact of the float being reduced in area to avoid sticking of the float in the seat or to the bottom of the cage and resultant failure of operation.

85 At a point intermediate its ends, the float 39 is provided with openings 43, so that the 90 float really constitutes two separate members, the upper or lifting portion having the valve head thereon and the lower weight member, which may be said to comprise a bucket, being suspended from the upper 95 member by straps 44, which support the bucket from the float end.

Leading from the thermostatic check valve 36, is a conduit 45, which leads into a vacuum control trap 46.

100 The trap 46 comprises a metallic, cylindrical body 47, the lower end of which is threaded into the restricted upper end of a base cup 48 for containing a sealing medium such as mineral oil or other suitable liquid.

105 Threaded onto the upper end of the body cylinder 47 is a cap 49, having a plurality of apertures 50, through which air may be discharged from the cylinder after passing through the liquid seal in the cup 48, the cap 110 being connected by a neck 51 with a spherical vacuum chamber 52, having a boss 53 there-

on, into which a pipe 54 is threaded and which latter provides connection with the air line pipe 45.

Extending from the vacuum chamber 52,

- 5 concentrically with the cylinder 47 and terminating below the level of the liquid seal, is a conduit 56, through which air delivered from the radiators is discharged into the cups 48 and thence to atmosphere through
- 10 the apertures 50 in the cap 49; the conduit being provided at its discharge end with a check valve which is located below the liquid seal and comprises an L fitting 58, having a valve flap 59 hinged over its discharge end
- 15 adapted to open outwardly to permit a discharge of air from the conduit 56 and to close the opening when a vacuum is created within the system.

In order to prevent air from being drawn into the pipe system when a sufficient vacuum has been created therein, I provide an automatic valve 60, comprising a closed cup 61 which is divided by a flexible diaphragm 62 into chambers 63—63'; the chamber 63 being open to atmosphere through a port 64 in the top of the cup, and the lower chamber connecting by means of a neck 65 that is threaded to receive the pipe 54 with the valve cap 49 and through a side opening 66

- 30 and pipe 67 with the pipe 45. Mounted in the under side of the diaphragm is a valve stem 68 which carries at its lower end a valve adapted to seat over and to close the opening of the pipe 54; the valve being normally held open by a spring 70 which encloses the stem 68 and bears upwardly on the diaphragm but when sufficient vacuum is created within the system the diaphragm is drawn downwardly against tension of the
- 35 spring and the valve 69 seated within the pipe 54 to close connection between the trap 46 and pipe system to prevent any intake of air.

Assuming that the parts are so constructed and connected with the boiler and radiators by the pipes as described, the operation of the system is as follows:

When the boiler is heated, steam is driven through the main 2, and by the risers 3 is delivered by adjustment of the valves 4 into the radiators 6 in any quantity desired.

Water of condensation delivered from the pipe 26 will flow into the receiver and accumulate therein, air from the pipe passing out through the vent pipe 35. As the receiver fills, the water lifts the float 39 until the latter closes the valve seat in the collar 32 to prevent the escape of water through the vent pipe.

With the receiver sealed, pressure therein is increased until it eventually balances that in the boiler and when the equalization occurs the check valve 30', located in the boiler connection, opens and the water in

65 the receiver flows into the boiler. When the

receiver is emptied of the condensation water, the float returns from its seat in the collar and opens the vent so that the operation just described, may be repeated.

Air discharged from the vent pipe passes 70 through the thermostatic valve 36 and, by the pipe 45, is delivered into the vacuum control trap 46, where it passes through the liquid seal and escapes to atmosphere through the apertures 50.

75 It will be seen that with the system heated and the mains and radiators filled with steam, practically all the air will be driven therefrom through the pipes 25 and water of condensation will be passed through the 80 valve 5 and delivered ultimately back to the boiler.

As heat diminishes and steam ceases to be generated, the steam contained in the pipe system gradually condenses, and as the return of air to the system is prevented by the liquid seal in the controller, vacuum is produced in the system which will continue to draw heated vapor through the system after 90 temperature in the boiler has fallen below the atmospheric boiling point, and will, when the fire has been replenished, cause a quick circulation of steam to all parts of the system.

95 It is apparent that by so constructing the system steam may be delivered into the top of the radiators and the air and vapor discharged therefrom into the receiver separator 27, where the water is delivered back to the boiler and the air discharged through 100 the trap 46 to atmosphere.

It is also apparent that the special construction of the valve 5 will effectively prevent any intake of steam at the base of the radiators, but will permit the discharge of 105 water of condensation therefrom, and that when the radiators and pipes become filled with steam the automatic valve 36 will close to prevent discharge of steam from the system through the trap 46, and the valve 30' 110 will be forced open by the resultant equalization of pressure in the separator to permit the flow of water of condensation back to the boiler.

With the system so arranged, a very low 115 pressure in the boiler will effectively produce the required circulation through the system and, due to the created vacuum therein, the system will retain the heat longer and produce a quicker circulation than is ordinarily acquired.

Having thus described our invention, what we claim as new therein, and desire to secure by Letters-Patent, is—

1. An air trap comprising a vertical cylinder having a water seal at the bottom thereof and ports leading to atmosphere at the top, a chamber above the cylinder, a pipe leading from the chamber to the water seal, an air port leading to the chamber, and a 125
- 130

pressure responsive valve normally closing said port to the chamber.

2. An air trap comprising a vertical cylinder having a water seal at the bottom thereof and ports leading to atmosphere at the top, a chamber above the cylinder, a pipe leading from the chamber to the water seal, an air port leading to the chamber, and a pressure responsive valve mechanism normally closing the inlet to said port, said mechanism comprising a casing having an air inlet port, a diaphragm in said casing and a valve connected to the diaphragm.
- 10

3. An air trap comprising a cylindrical casing having a water seal at one end and 15 air ports communicating with atmosphere at the other, a pipe extending into the casing and having its lower end submerged below the water seal, means for introducing air into the pipe, and a pressure-actuated 20 valve normally closing the pipe.

In testimony whereof we affix our signatures.

JOHN H. BLEDSOE.
MARTIN HAUSER.
